UNITED STATES PATENT OFFICE.

JOSEPH P. WALSH, OF VANCOUVER, BRITISH COLUMBIA, CANADA.

WOOD-REFUSE BURNER.

1,339,729.

Specification of Letters Patent. Patented May 11, 1920.

Application filed August 13, 1919. Serial No. 317,292.

To all whom it may concern:

Be it known that I, JOSEPH P. WALSH, a citizen of the United States, residing at Vancouver, in the Province of British Columbia, Canada, have invented certain new and useful Improvements in Wood-Refuse Burners, of which the following is a specification.

This invention relates to a burner for the destruction of combustible refuse, such as that of lumber mills. It belongs to that class known as "air-cooled" wherein a grate surface onto which the refuse to be consumed is delivered and through which a supply of air for combustion is indrawn by the natural draft of the fire, is surrounded by a self-supporting frusto-conical casing, around the lower edge of which air is freely admitted to keep the casing wall cool.

In furnaces of this class it has heretofore been considered necessary or desirable to provide an inner wall, retaining the fire within the limit of the grate and deflecting upward the air admitted around the lower edge of the casing.

This construction is open to objection in that in strong wind fire is blown out around the lower edge of the casing, or the same may occur by an occasional back fire. To these casualties objection is taken by the fire underwriters as they endanger the structure of the refuse delivery conveyer and adjacent parts.

Further, the fire underwriters require that the upper end of the burner smoke-stack be protected with a dome screen of relatively fine mesh to prevent escape of flying particles of light wood. This screen being clear of the fire, it is found exceedingly difficult to keep clear of accumulation of light, partially consumed wood refuse, which is carried up by the draft and adheres to the screen, completely clogging it in a short time and destroying the efficacy of the burner.

These several objections, and others to which attention will be drawn, I have overcome in the burner described in the following specification by dispensing with the circular fire retaining wall, or that portion of it which projects above the fire grate, and providing instead a mesh screen around the lower part of the frusto-conical casing. This screen retains the fire within its limit, and permits a cooling current of air to pass up the inner side of the casing. It also

effectively prevents the escape of flame or fire during a strong wind or a back fire.

Again, I supplement the customary screen at the top of the smoke-stack with a conical screen of coarser mesh adjacent to the base of the same, or at the junction of the cylindrical smoke-stack to the frusto-conical casing, and to prevent the excessive draft caused by a smoke-stack of sufficient height to satisfy the requirements of the fire underwriters, I provide a series of closable apertures at the base of the cylindrical smoke-stack between the two screens, by which the draft may be regulated.

The invention is fully set forth in the following specification, reference being made to the drawings by which it is accompanied, in which:

Figure 1 is a partial elevation and vertical longitudinal section through the burner.

Fig. 2 is a partial plan of the base of the same.

Fig. 3 is an enlarged detail of the lower end of the inclosing casing or shell of the burner and its connection to the grate wall.

In these drawings 2 represents an externally buttressed wall across the inclosed area of which are air ducts 3 and 4 crossing one another at right angles. Adjacent the intersection the air admission ducts 3 and 4 are covered by grate bars 5 through which air for combustion is supplied to the fire. The spaces 6 bounded by the circular wall 2 and air duct walls 3 and 4 are filled in with earth to approximately the level of the outer wall 2.

Resting on and secured to the wall 2 of the grate area as a foundation, with the upper ends secured to a ring 11, a framework of inwardly sloped angle iron uprights 7 is erected, which is braced at intervals by pipe rings 8.

On this framework a casing or shell 9 of thin sheet metal is secured, forming a hollow conical frustum from a short distance above the level of the furnace grate to the upper ring 11. From this upper ring 11 a cylindrical extension 12 is carried upward as a smoke-stack to a height sufficient to satisfy the requirements of the insurance board of underwriters. Around the space between the level of the grate surface and the lower edge of the casing 9 a screen 13 of stout wire mesh is secured to retain the fire on the grate and prevent it being blown

out from the grate by a strong wind or back fire.

An upwardly projecting conical screen 14 is introduced approximately at the junction 5 of the smoke-stack 12 to the conical casing 9 and the cylindrical smoke-stack 12 is sur- mounted with a spark arresting wire mesh screen or hood 15.

Between the screens 14 and 15 a series of 10 air admission apertures 16 are provided which are adapted to be closed in any convenient manner, preferably by slideable or pivoted doors.

The wood refuse is delivered at 15 toward the center of the grate in the manner usual with such burners, and is consumed thereon largely by the air admitted through the ducts 3 and 4, and the heat of its combustion induces the inflow of the air by which it is 20 consumed. The screen 13 prevents the material to be burnt falling beyond the limit of the grate and the flame and light wood being blown beyond the range of the burner. It also permits an inflow of air to cool the 25 inner wall of the casing 9 and its framework.

In burners of this class where an over-delivery of refuse may at any time cause, for a short time, an excessive delivery of 30 smoke, when the flame breaks through, the gases ignite and may form a dangerous blow back, the flame cannot escape through the screen 13.

The screen 14 prevents the escape of the 35 lighter portions of the refuse lifted from the fire by the draft and holds them in reasonable proximity to the flame of the fire, where they are periodically consumed, the air rising up the inner wall of the casing 40 and heated during such ascent supplying the necessary oxygen for such combustion.

The screen 15 at the top of the smoke-stack affords an additional security against the escape of sparks which renders the 45 burner extra safe in meeting the requirements of the fire underwriters.

As the smoke-stack 12 has to be carried to an elevation to meet the requirements of the fire underwriters and as that height may 50 in some cases induce too strong a draft through the fire, that draft may be checked when found necessary by opening the doors 17 of the aperture 16.

Having now particularly described my in- 55 vention, I hereby declare that what I claim as new and desire to be protected in by Letters Patent, is:

1. A wood refuse burner, comprising the combination with a circular hearth to which 60 the refuse to be burned is delivered, of a frusto-conical casing suitably supported

thereabove, the lower edge of which casing is a short distance above the hearth, a smoke-stack extending upward from the smaller end of the casing, a screen across the 65 smoke-stack adjacent its connection to the casing, and a screened hood across the top of the smoke-stack.

2. A wood refuse burner, comprising the combination with a circular hearth to which 70 the refuse to be burned is delivered, of a frusto-conical casing suitably supported thereabove, the lower edge of which casing is a short distance above the hearth, a smoke-stack extending upward from the 75 smaller end of the casing, said stack provided with apertures intermediate of its length, dampers for closing said apertures, a screen across the smoke-stack adjacent its connection to the casing, and a screen across 80 the upper end of the same.

3. A wood refuse burner, comprising the combination with a circular hearth to which the refuse to be destroyed is delivered, a frusto-conical casing suitably supported to 85 inclose the fire on the hearth, the lower edge of said casing being a short distance above the level of the hearth, a screen extending between the hearth level and the lower edge 90 of the casing to close the space between the hearth and the lower edge of the casing, a substantially cylindrical smoke-stack extending upward from the smaller end of the casing, said smoke-stack having openings 95 adjacent the connection to the casing, dampers for closing said openings, a screen across the lower end of the smoke-stack below the openings, and a screen across the upper end of the stack.

4. A wood refuse burner, comprising the 100 combination with a circular hearth to which the refuse to be burned is delivered, said hearth having air delivery ducts and grate bars covering the inner ends of the same, a frusto-conical casing suitably supported to 105 inclose the fire on the hearth, the lower edge of said casing being above the level of the hearth, a screen between the level of the hearth and the lower edge of the casing to close the space between the hearth and the 110 lower edge of the casing, a substantially cylindrical smoke-stack extending upward from the smaller end of the casing, said smoke-stack having apertures adjacent to its place of connection to the casing, dampers for closing said apertures, a screen across the smoke-stack below the closable apertures, and a screen across the upper end 115 of the smoke-stack.

In testimony whereof I affix my signature. 120

JOSEPH P. WALSH.
